US00D723055S

(12) **United States Design Patent**
Francisco et al.

(10) **Patent No.:** **US D723,055 S**
(b4) **Date of Patent:** **** Feb. 24, 2015**

(54) **DISPLAY SCREEN WITH GRAPHICAL USER INTERFACE**

(71) Applicant: **Microsoft Corporation**, Redmond, WA (US)

(72) Inventors: **Jesse Francisco**, Redmond, WA (US); **Stephen Danton**, Seattle, WA (US); **Jonah Sterling**, Redmond, WA (US); **Michael Bach**, Redmond, WA (US); **Jon Harris**, Redmond, WA (US); **Jon Lee**, Redmond, WA (US); **Jodie Eilers**, Redmond, WA (US); **Dina-Marie LeDonne Supino**, Redmond, WA (US); **Jefferson King**, Redmond, WA (US); **Karandeep Anand**, Redmond, WA (US); **William Staples**, Redmond, WA (US); **Adam Abdelhamed**, Redmond, WA (US); **Muhammad Bilal Aslam**, Redmond, WA (US); **Madhur Joshi**, Kirkland, WA (US)

(73) Assignee: **Microsoft Corporation**, Redmond, WA (US)

(**) Term: **14 Years**

(21) Appl. No.: **29/448,882**

(22) Filed: **Mar. 14, 2013**

(51) LOC (10) Cl. **14-04**

(52) U.S. Cl. ....

USPC **D14/486**

(58) **Field of Classification Search**

CPC G06F 3/048

USPC D14/485-495; 715/700-978

See application file for complete search history.

Assistant Examiner — Richelle G Shelton

(74) Attorney, Agent, or Firm — Banner & Witcoff, Ltd.

(57) **CLAIM**

The ornamental design for a display screen with graphical user interface, as shown and described.

DESCRIPTION

The FIGURE is a front view of a display screen with graphical user interface showing our new design.

The broken line showing the remainder of the display screen is for environmental purposes only and forms no part of the claimed design.

1 Claim, 1 Drawing Sheet
